L. ABEND.
CIRCUIT BREAKER.
APPLICATION FILED MAR. 29, 1917.

1,279,631.

Patented Sept. 24, 1918.

UNITED STATES PATENT OFFICE.

LOUIS ABEND, OF MERIDEN, CONNECTICUT, ASSIGNOR TO THE CONNECTICUT TELEPHONE & ELECTRIC COMPANY, INC., OF MERIDEN, CONNECTICUT, A CORPORATION OF CONNECTICUT.

CIRCUIT-BREAKER.

1,279,631.

Specification of Letters Patent. Patented Sept. 24, 1918.

Application filed March 29, 1917. Serial No. 158,211.

To all whom it may concern:

Be it known that I, LOUIS ABEND, a citizen of the United States, residing at Meriden, in the county of New Haven and State 5 of Connecticut, have invented a new and useful Improvement in Circuit-Breakers; and I do hereby declare the following, when taken in connection with the accompanying drawings and the characters of reference 10 marked thereon, to be a full, clear, and exact description of the same, and which said drawings constitute part of this application, and represent, in—

Figure 1 a plan view of one form which 15 a circuit-breaker constructed in accordance with my invention, may assume.

Fig. 2 a view thereof in longitudinal section on the line 2—2 of Fig. 1.

Fig. 3 a sectional view thereof on the 20 line 3—3 of Fig. 1.

Fig. 4 a detached perspective view of the carrier.

Fig. 5 a similar view of the adjustable mounting-plate.

Fig. 6 a similar view of the insulating sheet.

Fig. 7 a similar view of the fixed mounting-plate.

Fig. 8 a plan view of one of the modified 30 forms which my improved circuit-breaker may assume.

My invention relates to an improved circuit-breaker for the ignition system of internal combustion engines, the object being 35 to produce a simple, compact, durable, reliable and highly efficient device constructed with particular reference to the maintenance of the parallelism of the contacts, notwithstanding their adjustment for 40 varying their separation as may be required for whatever purpose.

With these ends in view, my invention consists in a circuit-breaker having certain 45 details of construction and combinations of parts as will be hereinafter described and pointed out in the claims.

In carrying out my invention as herein shown, a contact 4 is mounted in the end of a contact-spring 5 having its opposite 50 end bent at a right angle and secured by a rivet 6 to an integral arm 7 standing at a right angle to a mounting-plate 8 fastened by rivets 9 to a pivotal adjusting-plate 10

from which it is insulated by a sheet 11 of fiber insulation perforated at 12 for the passage through it of the rivets 9 which in turn are insulated from the mounting-plate 8 by flanged, insulating bushings 13. The said plate 10 is formed with holes 14 for the reception of the rivets 9, while the plate 8 is 60 formed with holes 15 for the same purpose.

The complementary contact 16 is riveted into an inwardly turned finger 17 offsetting from an arm 18 made integral with and standing at a right angle to an adjustable 65 mounting-plate 10 which is formed with a bearing-hole 19 by which it is pivotally mounted upon a stud 20 in an oscillatory plate-like carrier 21 having a central bearing-opening 22 receiving a concentric annular bearing-shoulder 23 rising from the bottom of a cup-like body or casing 24 within which the parts of my improved circuit-breaker are contained, the said body being provided in practice with a cover which is 75 not shown.

For the adjustment of the contacts 4 and 16, I form the plate 10 with an elongated slot 25 receiving a clamping-screw 26 entering a threaded opening 27 in the carrier 21. 80

The said carrier 21 is provided with a spark-controller arm 28 secured to it by rivets 29. A clearance slot 30 formed in the carrier 21 provides for the clearance of the inner ends of the rivets 9 as well as for 85 the clearance of a terminal piece 31 to which an electric wire 32 is secured, and which is secured to the plate 8 by means of a screw 33 provided for by a hole 34 therein. (Fig. 7). The plate 10 is also provided with a 90 large opening 35 for the clearance of the terminal-piece 31, also passing through a hole 36 in the fiber sheet 11. A helical spring 37 encircling the stud 20 and held in place by a cotter-pin 38, exerts a constant 95 effort to hold the plate 10 down upon the carrier 21.

The contact spring 5 is provided with an insulating button 39 made of fiber, mica or equivalent substance, and successively engaged by the high points 40 of a four-point cam 41 located at the outer end of a shaft 42 having bearing in the body 24 and driven from any source of power,—commonly from the cam-shaft of the engine.

In the operation of my improved device,

the contact 4 is separated from the contact 16 by the successive engagement of the high points 40 of the cam 41 as the same rotates. The amount of separation effected in this 5 manner will depend upon the normal relative position of the button 39 to the cam 41. Therefore to increase or decrease the separation of the contacts 4 and 16, as may be required to take up wear, to adapt the device 10 for use with different types of engines, &c., the button 39 must be swung toward or away from the cam 40 and so repositioned with respect thereto. For this purpose, the screw 26 is unscrewed and the adjusting- 15 plate 10 swung on its stud 20 until the desired position of the button 39 with relation to the cam has been secured, after which the screw 26 is screwed down to clamp the plate 10 upon the carrier 21. Inasmuch as 20 these contacts 4 and 16 are at this time swung upon the same center, that is, upon the stud 20, the parallelism of their faces is maintained; whereas in circuit-breakers as heretofore constructed, their adjustment for 25 changing the separation of their contacts has destroyed the parallelism of the faces thereof.

In the modified construction of my improved circuit-breaker, shown by Fig. 8, the 30 contact 43 is mounted in the outer end of a semi-circular mounting-arm 44, while the complementary contact 45 is mounted in a corresponding semi-circular mounting-arm 46, both of the said arms being hung upon 35 a stud 47 and insulated from each other by a suitable insulating washer 48. The said arm 46 is formed with an adjusting slot 49 receiving a clamping-screw 50 entering a circular carrier-plate 51 resting upon the 40 bottom of the cup-like body 24. The semi-circular arm 44 carries a cam-roller 52 of insulating material turning upon a stud 53 in the said arm and successively engaged by the high points 40 of a cam 41 located upon the 45 outer end of the shaft 42. A contact-spring 54 attached to a finger 55 upstanding from the said arm 44 bears against an insulated stud 56 mounted in the arm 46, and exerts a 50 constant effort to maintain the contacts 43 and 45 in engagement. When the shaft 42 rotates, the high points 40 of the cam 41 successively engage with the cam-roller 52, whereby the contact 43 is separated from the contact 45 to a greater or less degree dependent upon the particular adjustment of 55 the mounting-plate 46 at the time. The degree of their separation is regulated by loosening the screw 50 after which the arm 46 may be moved, as desired, and inasmuch 60 as it swings on the stud 47 which is also the center of the arm 44, it follows that any adjustment of the contact 45 must always be with its face parallel with the face of the contact 43.

65 It will thus be seen that both forms here-

in shown and described of my improved circuit-breaker, provide for the maintenance of parallelism in the faces of the contacts when the device is adjusted to change the amount of their separation for any purpose. Ordinarily the cover of the body 24 will mount a distributor for use in conjunction with the circuit-breaker, but forming no part of my present invention.

Furthermore, under my invention, the alignment of the contacts is also maintained regardless of adjustments for varying the amount of their separation. Heretofore, when one of the contacts has been rotated for varying the amount of their separation, the parallelism of their faces has been destroyed and their proper engagement prevented.

I claim:—

1. In a circuit-breaker, the combination with a carrier, of an adjustable mounting-plate carried thereby, a contact mounted thereon, an insulated mounting-plate imposed upon the said adjustable mounting-plate for movement therewith, a contact-spring fastened to the said insulated mounting-plate, a contact carried by the said spring, and means engaging with the said spring for separating the two contacts for breaking the circuit, whereby by adjusting the adjustable mounting-plate with respect 95 to the said actuating means, the degree of the separation of the contacts may be adjusted without altering the parallelism of their engaging faces.

2. In a circuit-breaker, the combination with an oscillating carrier, of an adjustable mounting-plate pivotally mounted thereupon, a contact mounted in the said plate, an insulated mounting-plate imposed upon the said adjustable mounting-plate, a contact-spring fastened to the said insulated mounting-plate, a contact carried by the said spring, an insulating contact-button also carried by the said spring, and a cam engaging with the said button for separating the contacts and breaking the circuit, the adjustment of the said adjustable contact-plate providing for varying the degree of the separation of the contacts without affecting the parallelism of their engaging faces.

3. In a circuit breaker, a main support or housing, a rotatable shaft therein, a cam on said shaft, a carrier carried by said support and angularly adjustable around and relatively to the axis of said shaft, two normally engaged contacts and means for mounting them on said carrier for adjustment around a common center at one side of said shaft, whereby the degree of separation of said contacts by the action of said cam may be varied without disturbing the parallelism of the engaging faces of said points.

4. In a circuit breaker, a stationary support or housing, a rotatable shaft entering said housing in substantially the center, a

cam on said shaft, a carrier adjustably mounted in said support for rotation relatively thereto, two normally engaged contacts and means for mounting them on said

5 carrier for adjustment around a common center at one side of said cam, whereby the degree of operation of said contacts by the action of said cam may be varied without

disturbing the parallelism of the engaging faces of said points. 10

In testimony whereof, I have signed this specification.

LOUIS ABEND.

Witness:

MALCOLM P. NICHOLS.
